Primary Examiner—Charles A Rademaker*Assistant Examiner*—Charles D Hanson(74) *Attorney, Agent, or Firm*—Morrison & Foerster LLP(57) **CLAIM**

The ornamental design for a foldable stroller, as shown and described.

DESCRIPTION

FIG. 1 is a front perspective view of a foldable stroller, showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is an overhead plan view thereof; and,

FIG. 7 is a bottom plan view thereof.

The features shown in broken lines are for illustrative purposes only and do not form part of the claimed design.
